UNITED STATES PATENT OFFICE.

ESEK BUSSEY, OF TROY, NEW YORK, ASSIGNOR OF ONE-HALF OF HIS
RIGHT TO CHARLES A. MCLEOD, OF SAME PLACE.

STOVE AND FURNACE GRATE.

SPECIFICATION forming part of Letters Patent No. 223,988, dated February 3, 1880.

Application filed August 4, 1879.

To all whom it may concern:

Be it known that I, ESEK BUSSEY, of the city of Troy, county of Rensselaer, and State of New York, have invented a new and useful Improvement in Stove and Furnace Grates, 5 of which the following is a specification.

My invention relates to a manner of constructing and arranging a stove or furnace grate; and it consists in forming upon the periphery of the grate downwardly-projecting feet, and upon the inside of the ash-chamber or deflecting dust-ring curved ways for the grate-feet and grate to rotate in when vibrated horizontally by means of a shaking-bar.

15 My invention also consists in a manner of combining with a stove or furnace grate that is arranged to vibrate horizontally in rotation by means of downwardly-projecting feet and curved ways for the latter, formed in the ash-chamber wall or deflecting dust-ring, a movable center and attached shaker-bar that will draw out, so as to leave an opening in the center of the grate, through which refuse material or the contents of the fire-chamber may 20 pass to the ash-pit, the object of my improvement being to dispense with the central rotating pin and cross-bar by which the grate is usually operated, and to make a free opening in the latter, unimpeded by the former, when it 25 is desired to discharge the contents of the fire-chamber into the ash-pit.

In the accompanying drawings there are three figures, in all of which like reference-letters designate the same parts of the device.

30 Figure 1 shows, in perspective, a view of the grate in position, and also the manner of arranging the downwardly-projected peripheral feet upon the former, and the curved ways for the grate and feet to move in when rotated horizontally by means of the shaking-bar, with the guideways for the feet to move in formed upon the adjoining wall upon its inner side. This illustration also shows the slotted opening formed in the wall to regulate the distance 35 and measure of horizontal grate-rotation. Fig. 2 shows a top view of the grate with the movable center drawn out and the supplemental bar attached to it; also the bar attached to the grate-perimeter, as well as the downwardly-projected feet. This illustration also

shows grooves or supporting-flanges formed on the grate to receive and support the movable center. Fig. 3 exhibits a top view of the movable grate-center separated from the grate.

The several parts which co-operate to produce my invention as constructed and arranged are designated as follows: The grate is shown at G, its downwardly-projecting feet at F F F, the curved guideways for the latter to move in when the grate is rotated at W W W W, 55 the supporting-bar attached to the rim of the grate at B', and the projecting shaking-bar attached to the movable center C is shown at B".

At O, Fig. 2, is designated the central opening produced when the movable center is drawn 60 forward.

The letter D shows the position of the slot formed in the wall to regulate the horizontal vibration of the grate and shaking-bar.

S S denote flanges, formed at the sides of 65 the opening O in the grate, which produce the grooves g g g g, in which the sliding center-piece C is arranged to move when drawn out or pushed in.

M M denote the wall of the ash-pit or deflecting "dust-ring," as sometimes called, it being the part in which the guiding-ways W W W are formed for the grate and grate-feet to 70 rotate in.

I am well aware that a grate having a movable center arranged to draw out, and constructed to vibrate in rotation by means of parallel ways formed in a supplemental grate-frame and ring, has been used before and patented.

I am also aware that a grate having a center-piece constructed to draw out, with the grate arranged to vibrate in rotation upon metallic balls working in a groove formed in a supplemental grate, has also been patented.

The leading feature of my invention being the manner of arranging the grate to shake in rotation horizontally by means of downwardly-projecting feet formed upon the grate and guiding-ways in the adjoining wall or ash-pit 95 wall, the movable center may be dispensed with, and the grate have in other respects the ordinary form, and still the other parts will perform their same office.

Having thus described my invention, what 100

I claim, and desire to secure by Letters Patent, is—

1. A circular stove or furnace grate having downwardly-projected supporting feet, and combined to operate in connection with curved ways formed in the adjoining ash-pit wall below the grate when the grate is vibrated in horizontal vibration, as herein shown and described.
2. In combination and arranged to co-operate with a stove or furnace grate that is constructed to rotate and vibrate horizontally by means of downwardly-projected feet and curved

ways upon the adjoining wall, a removable center that can be drawn out or moved in through grooves formed in the grate, and so as to open and close an opening in the grate, in the manner and for the purposes shown and described.

Signed at Troy, New York, this 28th day of June, 1879.

ESEK BUSSEY.
